[57] CLAIM

The ornamental design for a plural medicine vial supporting tray and cover, substantially as shown and described.

DESCRIPTION

FIG. 1 is an exploded front perspective view of the plural medicine vial supporting tray and cover, embodying my new design, with the cover shown in open position;

FIG. 2 is a top rear perspective view of the same, with the cover in closed position;

FIG. 3 is a bottom front perspective view of the same;

FIG. 4 is a fragmentary vertical section view, taken along the line 4—4 of FIG. 2; and

FIG. 5 is a front upper perspective view of the tray portion thereof, with the cover and vials removed.
